[57] CLAIM

The design for a dental locator for positioning denture,
substantially as shown and described.

DESCRIPTION

FIG. 1 is a front left perspective view of a dental locator
for positioning denture showing my new design;
FIG. 2 is a right side elevational view of the same;
FIG. 3 is a rear elevational view;
FIG. 4 is a bottom plan view; and
FIG. 5 is a top plan view.
